UNITED STATES PATENT OFFICE.

JOHN A. RUDISILL, OF LEWISTOWN, MONTANA.

TOY.

1,250,024.

Specification of Letters Patent. Patented Dec. 11, 1917.

Application filed August 1, 1917. Serial No. 183,919.

To all whom it may concern:

Be it known that I, JOHN A. RUDISILL, a citizen of the United States, residing at Lewistown, in the county of Fergus and 5 State of Montana, have invented new and useful Improvements in Toys, of which the following is a specification.

This invention relates to toys, and comprehends the provision of a device designed 10 for shooting marbles or similar projectiles, the toy being very simple in construction, and convenient to handle and manipulate for the purpose intended.

The nature and advantages of the invention 15 will be better understood when the following detail description is read in connection with the accompanying drawing, the invention residing in the construction, combination and arrangement of parts as 20 claimed.

In the drawing forming part of this specification like numerals of reference indicate similar parts in the several views and wherein:—

25 Figure 1 is a perspective view of the device constructed in accordance with my invention.

Fig. 2 is an edge elevation showing the 30 position of parts just prior to the shooting of the projectile.

Fig. 3 is a longitudinal sectional view.

Fig. 4 is a transverse sectional view.

The device forming the subject matter of my invention consists of an elongated 35 body member 10, which may be constructed from any suitable material, but preferably made of a narrow strip of wood or the like. The body 10 is formed to provide an extension 11 which projects an appreciable distance beyond one extremity of the body and 40 to one side of said end, and the purpose of this extension will be hereinafter set forth. One face of the body portion 10 which is disposed at right angles to the extension, is 45 cut away for a portion of its length, and defines a shoulder 12 upon which one extremity of a leaf spring 13 or the like rests. The cut away portion permits the spring to normally lie substantially within the 50 plane of the body, while the spring is of such length as to project beyond one end of the body, terminating substantially flush with the extension 11. The spring 13 may be secured to the body in any suitable manner, but by preference a threaded fastening 55 element 14 passes through alined opening

ings in the spring and body, and has associated therewith a nut 15 as shown. Manifestly, the spring is secured adjacent one end so that the spring is permitted to be 60 flexed, as it is through the inherent qualities of the spring that the marble or the like is projected. The extension 11 is disposed in right angular relation with the spring 13, and these parts coöperate to 65 hold the marble or the like against casual derangement upon the adjacent extremity of the body 10. The body 10 serves in the capacity of a handle so that the device can 70 be conveniently used by small children.

The side of the body 10 against which the spring is arranged, is provided with a recess 16, and a shaft 17 is suitably journaled in the recess, extending transversely of the body and projecting slightly beyond 75 one edge thereof. Carried by the shaft is a right angularly disposed extension, which provides a manipulating portion 18 for partly rotating the shaft, and by preference this manipulating portion forms an in- 80 tegral part of the shaft. If desired, the shaft and manipulating portion may be constructed from wire and may vary in design in the production of a device suitable for the purpose indicated. Carried by the shaft 85 17 is a lug 20 which normally assumes a position within the recess 14, lying in parallelism with the spring 13, thus permitting the latter to contact the adjacent side of the body 10. In practice, when the shaft 17 is 90 rotated in a direction to project the lug 20 from the recess 15, the spring is caused to assume the position illustrated in Fig. 2, in which position the spring is placed under tension. It is to be understood that the 95 marble or other device rests upon the upper extremity of the body portion, and when the shaft is rotated in a reverse direction to position the lug within the recess, the spring forcibly assumes its normal position, 100 during which time the marble or other device is projected from the extremity of the body 10. The disposition of the manipulating portion 18 of the shaft is such that the device can be conveniently handled and manipulated with one hand, the device in addition to this fact being simple in construction, and can be manufactured and sold at a nominal cost.

It is believed that from the foregoing description the nature and advantages of the invention will be readily apparent, although

I desire to have it understood that what is herein shown and described constitutes the preferred embodiment of the invention, and is not to be considered restrictive, as such changes may be resorted to when desired as fall within the scope of what is claimed.

What is claimed is:—

1. A device of the class described comprising an elongated member, said member having a transverse groove in one side, a yieldable element secured to said side, covering said groove and projecting beyond one extremity of the said member, a rod arranged in said groove for rotation, a lug projecting from said rod and normally lying parallel with said yieldable element, and adapted to flex said yieldable element when the rod is turned in one direction for the purpose specified.
2. A device for shooting projectiles, comprising an elongated member, an extension projecting from one side of said member beyond one end thereof, and designed to support the article to be projected when the toy is held horizontally, a yieldable element secured to said member and projecting beyond said end, said element being disposed at right angles to said extension, and means for flexing said element for the purpose described.
3. A toy for shooting projectiles, comprising an elongated member, an extension projecting from one side of said member and beyond one end thereof, said extension being provided with a transverse groove for the reception of the article to be projected, and

adapted to retain said article therein when the toy is held horizontally, a yieldable element secured to one side of the member and projecting beyond said end, and means interposed between said member and element, and operable to flex the latter for the purpose described.

4. A toy for shooting projectiles, comprising an elongated member having a relatively broad end portion, an extension projecting from one side of the member beyond said end, said extension and end serving to support the article to be projected when the toy is held in either a vertical or horizontal position, said extension having a transverse groove on one face, a yieldable element secured to one side of said member and projecting beyond said end, said element being disposed at right angles to the extension, and means operable to flex said element for the purpose described.

5. A toy for shooting projectiles comprising an elongated member of substantially rectangular formation in cross section, an extension projecting beyond one end of the member and disposed longitudinally of the latter, a leaf spring secured at one end to the side of said member, said spring projecting beyond one end of the member and disposed at right angles to said extension and means interposed between said member and said spring for flexing the latter for the purpose specified.

In testimony whereof I affix my signature.
JOHN A. RUDISILL.
